UNITED STATES PATENT OFFICE

114,828

DESIGN FOR A CASING FOR DOOR CLOSING AND CHECKING DEVICE OR SIMILAR ARTICLE

Louis F. Schmidt, Chicago, Ill., assignor to Norton Lasier Company, Chicago, Ill., a corporation of Illinois

Application March 19, 1938, Serial No. 75,944

Term of patent 7 years

To all whom it may concern:

Be it known that I, Louis F. Schmidt, a citizen of the United States, residing in Chicago, in the county of Cook and State of Illinois, have invented a new, original, and ornamental Design for a Casing for Door Closing and Checking Device or Similar Article, of which the following is a specification, reference being had to the accompanying drawing, forming part thereof.

Figure 1 of the drawing is a perspective view of

a casing showing my new design; and Figure 2 is a rear elevational view of the casing shown in Figure 1.

The casing of this design has the same appearance when seen from the opposite perspective.

I claim:

The ornamental design for a casing for door closing and checking device or similar article, substantially as shown and described.

LOUIS F. SCHMIDT.
